UNITED STATES PATENT OFFICE.

RAYMOND F. LINDENMUTH, OF QUAKAKE, PENNSYLVANIA.

LOCK.

1,376,951.

Specification of Letters Patent.

Patented May 3, 1921.

Application filed May 15, 1919. Serial No. 297,322.

To all whom it may concern:

Be it known that I, RAYMOND F. LINDENMUTH, a citizen of the United States, residing at Quakake, in the county of Schuylkill and State of Pennsylvania, have invented and certain new and useful Improvements in Locks, of which the following is a specification.

My present invention relates to improvements upon the lock disclosed in my co-pending application Serial Number 267,196, and has for its object to provide improved constructions and arrangements of the various parts which are more efficient in practice and less expensive to manufacture, and at the same time to provide a lock which is impossible to pick, or open with an inappropriate key.

An important object of my invention resides in the provision of a locking means co-acting with the bolt for locking the same in an operative position, which locking means is protected from trifling, or opening by means of an unauthorized key, by means 25 which can only be moved to uncover the locking means by a proper key, and said means is normally engaged with said bolt when the same is in a locked position for preventing unauthorized retraction of the 30 bolt.

Another object of my invention resides in the provision of a locking detent for retaining the bolt in an unlocked position, and is so constructed that it will readily disengage 35 the bolt when a force is applied thereto, such as the insertion into the lock of a keeper.

Other objects and advantages of the invention will become apparent during the course of the following description.

40 In the drawings, forming a part of the description and wherein like numerals are employed to designate like parts throughout the same,

Figure 1 is a longitudinal vertical section 45 through the invention.

Fig. 2 is a longitudinal horizontal section of the same taken on the line 2—2 of Fig. 1.

Fig. 3 is a transverse section taken on the line 3—3 of Fig. 2.

50 Fig. 4 is a perspective view of the rectilinear movable bolt.

Fig. 5 is a longitudinal vertical section through the invention, showing the same in locked position.

Fig. 6 is a transverse section taken on the line 6—6 of Fig. 2.

Fig. 7 is a longitudinal horizontal section of a modified form of invention.

Fig. 8 is a perspective view of the sliding plates composing the combination, with the 60 means for normally retaining the plates in an operative or locked position, and

Fig. 9 is a perspective view of the lock applied to a switch lever by means of a particularly formed bracket forming the base 65 and sub-base of the lock.

In the drawings wherein for the purpose of illustration is shown a preferred embodiment of my invention, I have illustrated the lock mechanism in connection with a rectangular form of casing, but I do not desire to be limited to this particular form inasmuch as a circular casing or one of another suitable configuration can be used equally as well.

The keeper 10 in the present instance is shown in the form of an inverted U-shaped member, having its free ends secured to a suitable support 11, but I desire it to be understood that a keeper in the form of an upstanding flange having one or more openings therethrough to receive the corresponding number of fingers carried by the rectilinear bolt, may be employed if found desirable.

The base 12 of my improved lock is in the form of the movable section of a hasp, which has the stationary section thereof secured to any suitable support. Each corner of the base 12 is provided with a threaded opening, the lower end of which is countersunk to receive a screw 13. A transversely extending slot 14 is provided in the base, for the passage of the keeper 10. A sub base 15 is provided with a slot 16, corresponding 90 to the slot 14 in the base for alignment with the latter, and each corner of the sub-base is provided with a threaded aperture to align with the apertures in the base. The casing 17 of the lock consists of a top and four sides, 100 the lower edges of the sides being beveled to snugly fit upon correspondingly beveled edges of the sub base 15, so as to make the sub base invisible and to protect the contents of the casing. The lower edges of the 105 sides of the casing 17 are provided with an inwardly extending perforated ear 18 at each corner thereof, and the perforations

therein are threaded and aline with the apertures or openings through the base and sub base, so that the screws 13 may secure the casing to the sub base, and the sub base 5 to the base. By mounting the casing upon the base in this manner, it will be seen that access cannot be gained to the bottom of the base to loosen the screws 18 when the device is locked. As clearly shown in Figs. 10 2 and 3, the sub base is provided with a rectilinear slot 19 the sides of which are under cut for a purpose which will presently appear, and said slot extends from one end of the base to substantially the central portion thereof to communicate with and extend 15 beyond the slot 16.

The rectilinearly movable bolt 20 of my improved lock is provided with a dovetailed bottom 21 for reception in a similarly 20 shaped slot 19 of the sub base. This bottom 21 extends a substantial distance rearwardly of the rear end of the bolt. The bolt 20 is provided with a laterally extending 25 arm 22 and the upper face of the bolt is provided adjacent one end thereof with an upstanding pin 23. The bolt is normally urged across the slots 14 and 16 in the base and sub base by means of a spring 24 having one end secured to posts 25 mounted 30 upon the sub-base, and the opposite end of the spring rests upon the rearwardly extending portion of the dovetailed bottom 21 of the bolt and exerts a pressure against the rear end of the bolt.

35 The bolt is retained in its retracted position by means of a movable detent 26, which assumes the form of a bar having its outermost end bent at right angles to be received in an opening 27 in the sub base and normally retained therein by means of a coil 40 spring 28, which spring is retained in its proper position by means of a suitable bracket 29 secured to the sub base over the opening 27. The inner end 30 of the detent is adapted to engage with the forward 45 end of the bolt 20, when the bolt is in an unlocked position, and the detent is offset as at 31 so as to space the free end from the sub base and so that said free end engages 50 the bolt adjacent its upper edge. From this construction and arrangement, it will be evident that when the keeper 10 is inserted into the lock to engage the free end of the detent, very little pressure is needed to cause 55 upward movement of the detent whereby it is caused to disengage from the bolt and permit the bolt to move forwardly through the keeper to its locked position.

I provide a locking mechanism, 60 designated generally by the numeral 32, in order to retain the bolt in its locked position and to prevent trifling with the lock in an attempt to retract the bolt without the use of a proper key, and this locking mechanism is 65 arranged above the bolt a slight distance

from the free end of the detent 26. In the present instance, the locking mechanism is in the form of a pair of sliding tumblers 33 and 34, as more clearly shown in Fig. 8, and these plates are adapted to slide simultaneously across the bolt 20 and are retained in their proper position by means of a suitable guide bracket 35. Both plates are provided substantially intermediate their ends with an L-shaped slot 36, which slots receive the 70 pin 23 of the bolt therein when the bolt is in a locked position. As clearly shown in Fig. 8, the lower plate 34 is offset as at 37 adjacent its free end so that it may be spaced from the free end of the upper plate. 75 These plates extend laterally across the sliding bolt and their free ends 38 project beyond one side of the bolt and are arcuated transversely for engagement with the bit of a suitable key. To the rear end 39 of each 80 plate, is secured to the end a spring 40, and the opposite end 41 of the spring is embedded in a suitable groove in a spring retaining plate 42. In the present instance, there are two spring retaining plates 42 inasmuch as 85 there are two plates comprising the locking mechanism, and these plates 42 are secured to the sub base beneath one end of the bracket 35 by means of rivets 43 or the like. From this construction, it will be apparent that the 90 plates 33 and 34 are normally urged so that their free ends 38 project beyond the side of 95 the bolt.

The means I provide for protecting the 100 locking mechanism against trifling, or actuation with an inappropriate key, is a guard plate 44 which is vertically movable on the base through a slot in a supporting plate 45. This supporting plate is retained in spaced 105 relation of the sub base by means of supporting columns 46, through which pass screws 47 for retaining the plate 45 in its proper position. The bottom 48 of the guard 44 is curved and is provided with a 110 notch 49 to receive therein the laterally extending arm 22 of the sliding bolt when it is in a locked position. If preferred, this curved face 48 may be provided with pins 50 of varying lengths so that the bit of an 115 inappropriate key cannot engage the curved face to move the guard upwardly to expose the tumbler plates 33 and 34. The top 51 of the guard is flanged to overlie the edges of slot in the plate 45 so as to retain the guard 120 in position in the plate 45 when the sliding bolt 20 is retracted. A spring 52 has one end secured to the plate 45, while its free end is bent to frictionally engage with the flanged top of the guard 44. A key hole 53 is of course provided in the top of the casing 125 17 and also in the plate 45 adjacent one longitudinal edge of the guard 44, and a key post 54 is secured to the sub base 15 in order to retain the key in its proper position while it is being turned to open the lock.

When it is desired to lock the lock to its keeper 10 the lock or keeper carrying member as the case may be, is swung so that the keeper 10 is inserted through the slot in the base and sub base, which action causes the end of the keeper to force the free end of the detent 26 out of engagement with the forward end of the sliding bolt 20. As this abutment is relieved, the spring 24 will of course move the sliding bolt 20 rectilinearly forward so that the forward end of the bolt passes through the U shaped keeper to prevent displacement of the same from the lock casing. During the forward movement of the bolt, the pin 23 carried thereby will pass into the L shaped slots 36 in the plates 33 and 34 by sliding along the inclined walls 55 of the slots. When the pin abuts with the walls of the angularly disposed portions of these slots, the plates will be forced farther across the sliding bolt by means of their respective springs 40, which action will cause the pin 23 carried by the bolt to be locked within the L shaped slots 36 of the combination plates. From this, it will be manifest that the bit of retraction of the bolt is impossible until the plates have been moved to such position so as to permit the withdrawal of the bolt pin from the L-shaped slots in the plates.

Also, during the forward movement of the bolt, the lateral arm 22 thereof will be caused to engage the curved face of the guard 44 and elevate the same against the tension of its spring 52, until the recess 49 in the curved face is occupied by the laterally extending arm 22 which will cause the guard 44 to move downwardly to securely retain the arm 22 of the bolt in locked engagement therewith.

The locked position of the device is illustrated in Fig. 5 of the drawings, and when it is desired to unlock the device, an appropriate key is of course inserted through the key holes in the casing and plate 45 until it is positioned upon the key post 54. Then by turning the key in the usual manner, it will be permitted to pass the pins 50 on the curved face of the guard 44 so that it can engage the arcuated face of this member to elevate the same. The upward movement of the guard 44 of course exposes the curved ends 38 of the tumbler plates, and by further turning the key, it will engage said ends of the tumbler plates and move them rearwardly against the tension of their springs 40. This will cause the plates to move across the bolt 21 until the pin 23 thereof engages the angularly arranged walls of the slots 31. When the key has actuated these parts to the positions thus far outlined, by further turning the key it will engage with the laterally extending arm 22 of the sliding bolt and retract

the same so that the pin 23 thereof is totally disengaged with the slots 36 in the tumbler plates.

The keeper 10 may then be withdrawn from the lock since the detent 26 has been moved upwardly against the tension of its spring 28. During the outward movement of the keeper, the detent will move downwardly toward the sub base until the free end 30 is engaged with the forward end of the bolt 20. This detent of course prevents forward movement of the sliding bolt against the action of its spring 24.

In Fig. 7 of the drawings, wherein is shown a modified form of invention, it will be noted that the tumbler 32 in this instance is in the form of a swinging plate or plates 56, the free end or ends of which extend across and beyond the sliding bolt 20, and are provided with the L shaped slots 36. The opposite end or ends of these swinging plates are pivotally connected to a stationary plate 57 secured to the sub base by means of rivets 58 or the like. These tumbler plates are caused to normally extend across the sliding bolts by means of springs 59 carried by the plate 57. The other parts of the invention described above are also embodied in this modified form in the manner set forth.

When it is desired to use the lock in connection with switch levers, the base and sub base of the locks are formed by securing together the free ends of a piece of metal 60. The intermediate portion of this piece of metal is bent into suitable form to embrace the switch lever 61, and is secured to the lever by any suitable means. The keeper 10 in this particular instance is secured to a tie, and when the lever is swung to lock the switch, the lock is of course carried thereby and the keeper passes through the base and sub base in the manner outlined above.

The foregoing description and the drawings have reference to what may be considered the preferred, or approved form of invention. It is to be understood that I may make such changes in construction and arrangement and combination of parts, materials, dimensions, etc., as may prove expedient and fall within the scope of the appended claims.

Having thus fully described my invention, what I claim as new and desire to secure by Letters Patent, is:

1. In a lock, the combination with a bolt, a tumbler mechanism for the bolt, means disposed to prevent engagement of unauthorized tools with said tumbler mechanism, and said means adapted for retaining the bolt in a locked position, and being adapted to be engaged by a proper key and moved and the bolt retracted with one turn of said proper key.

2. In a lock, the combination with a bolt, a tumbler mechanism for the bolt, of movable means disposed to prevent engagement of unauthorized keys with said tumbler mechanism, and adapted to retain the bolt in a locked position, said means having means to prevent its being moved by an unauthorized key, and being adapted to be engaged by a proper key and moved and the bolt retracted with one turn of said proper key.
3. In a lock, the combination with a bolt; a tumbler mechanism for the bolt, of movable means disposed in the path of movement of a key to prevent engagement of an unauthorized key with the tumbler mechanism, and said means being capable of being engaged by a proper key and moved to permit engagement thereof with the tumbler mechanism.
4. In a lock, the combination with a bolt and a tumbler mechanism, of a movable guard for retaining said bolt in a locked position, said guard being disposed in the path of movement of a key to prevent engagement of unauthorized keys with the bolt and tumbler mechanism, said guard having a cam face, and an abutment thereon to prevent unauthorized keys acting upon said cam face, and said guard being capable of being moved by the proper key engaging said cam face to permit engagement of the key with the bolt and tumbler mechanism.
5. In a lock, a base, a supporting plate arranged in spaced relation to the base, a bolt slidable between the base and plate, a tumbler mechanism for the bolt, a movable

guard member mounted in the plate and cooperating with the bolt to lock the same against movement, said member being disposed in the path of movement of a key to prevent engagement of unauthorized keys with the bolt and tumbler mechanism, and said guard member being adapted to be moved by a proper key to permit engagement of the key with said bolt and tumbler mechanism.

6. In a lock, the combination with a sliding bolt having a laterally extending arm thereon, of a movable guard having a curved face and recess therein for reception of said laterally extending arm when the bolt is in a locked position, and a key adapted for engagement with said articulated face of said guard to move said guard out of engagement with said laterally extending arm whereby said key may engage the laterally extending arm to retract said bolt.

7. A lock, a key therefor, the combination with a tumbler mechanism, a movable guard disposed in the path of movement of said key to prevent unauthorized keys from engaging said tumbler mechanism, said guard having a curved face, and abutments on said curved face to prevent actuation of said guard by unauthorized keys.

In testimony whereof I affix my signature in presence of two witnesses.

RAYMOND F. LINDENMUTH.
